UNITED STATES PATENT OFFICE.

AARON ROSENBERG, OF PHILADELPHIA, PENNSYLVANIA, ASSIGNOR TO
MORRIS ROSENBERG, OF SAME PLACE.

LINIMENT.

SPECIFICATION forming part of Letters Patent No. 444,398, dated January 6, 1891.

Application filed November 11, 1890. Serial No. 371,056. (No specimens.)

To all whom it may concern:

Be it known that I, AARON ROSENBERG, a citizen of the United States, residing at Philadelphia, in the county of Philadelphia and State of Pennsylvania, have invented certain new and useful Improvements in Medical Compounds; and I do hereby declare the following to be a full, clear, and exact description of the invention, such as will enable others skilled in the art to which it appertains to make and use the same.

My composition consists of the following ingredients in about the proportions set forth: deodorized gasoline, three gallons; powdered capsicum, one pound; gum-camphor, one pound; alkanet-root, half a pound; oil of citronella, nine ounces; oil of origanum, one pound; oil of sassafras, half a pound. These materials are thoroughly commingled, and the composition is then filtered and placed in

bottles or other receptacles for commercial purposes.

The ingredients set forth and intermingled constitute a medical composition for internal and external use, for the treatment of rheumatism and many other diseases of the human system.

What I claim, and desire to secure by Letters Patent, is—

The herein-described medical compound, consisting of gasoline, capsicum, camphor, alkanet-root, oils of citronella, origanum, and sassafras, in the proportions named.

In testimony that I claim the invention above set forth I affix my signature in presence of two witnesses.

AARON ROSENBERG.

Witnesses:

E. C. WOLF,
WM. F. BELSTERLING.
